UNITED STATES PATENT OFFICE.

CHARLES J. SUTPHEN, OF PATERSON, NEW JERSEY.

TUCKING MEANS FOR KNITTING MACHINES.

Application filed December 13, 1922. Serial No. 606,609.

To all whom it may concern:

Be it known that I, CHARLES J. SUTPHEN, a citizen of the United States, residing at Paterson, in the county of Passaic and State 5 of New Jersey, have invented certain new and useful Improvements in Tucking Means for Knitting Machines, of which the following is a specification.

The principal object which the mechanism herein set forth is designed to subserve is to produce a unique and attractive fabric embodying the stitch known in the knitting art as the "tuck" or "lace" stitch, which is the result of the needle involved taking yarn 10 for one or more courses without looping the same through the loop already on the needle so that when it does loop yarn through such loop the yarn of any intervening course will be hung up on the new loop; stated more 15 fully, the principal object of said mechanism is to produce an article, such as hosiery, which in certain regions shall be circuitously composed entirely of lace stitches, in others of plain stitches, and in others in part of lace 20 stitches and in part of plain stitches, as at the foot. In carrying out this object I have further had in mind to construct the said mechanism so that it may be applied to a circular knitting machine without any 25 change in the existing mechanism of such machine beyond providing for rendering temporarily inactive an inconsiderable part 30 of the mechanism thereof.

I shall first state briefly and generally 35 the salient features of operation of that embodiment of my invention which is herein set forth by way of example and then describe the construction and operation in detail: Assuming my invention to be applied 40 to a knitting machine of the kind set forth in the Scott Patent No. 1,152,850, for example, that cam which elevates the needles to clear their latches preliminary to forming the stitches in continuous rotary knitting is 45 put out of action and two other cams for performing this service, but in a special way, perform the latch-clearing operation. On every other cycle (revolution of the needle group) both of these cams are active, one on a series of needles composed of 50 the alternate, and the other on a series composed of the remaining, needles; on the re-

maining cycles first one cam is active and the other inactive and then vice versa. This produces a pattern in which courses of plain 55 stitches (when both cams are active) alternate with courses of stitches (when one or the other cam is active) in which the alternates are plain and the remainder tuck 60 stitches, the pattern moreover having the tuck stitches in two adjoining courses of the latter kind staggered, so that one characteristic of the fabric is that it appears diagonally striped. The cams, which I term special cams, are made to act selectively as indicated (i. e., one on one needle-series and the other on the other) in the present instance through the medium of 65 two series of jacks. When the development of the fabric requires that a half or other 70 fragment of each circular course shall be composed entirely of plain stitches, as in knitting the rear-ankle portion of a hosiery article and later the instep portion, the special cams are left in action but whatever distribution as to latch-clearing these cams effect with respect to that fragment of the 75 needle-group which is to knit plain all such needles are made to assume the latch-clearing position before they come to the stitch-forming point in their circular path of 80 travel, this occurring in every cycle; the means for effecting this is a cam means which when used is brought into position to act on said fragment or part of the 85 needle-group and not on the remainder thereof, this being accomplished by using needles having butts of different lengths. Plain knitting throughout each circular 90 course, or knitting reciprocally as in the case of heels and toes, is accomplished by restoring the regular latch-clearing cam to working position, the said cam means being then inactive; the special latch-clearing 95 cams remain in action at such times (as in fact they do at all times) for they are positioned so that the needles are acted upon by them rotatively earlier than by the regular latch-clearing cam, so that when the latter is in action it in effect nullifies the distribution of the needles which the special 100 cams produce.

In the drawings,
Fig. 1 is a vertical sectional view, on ap-

proximately the line 1—1, Fig. 2, of the upper part of a knitting machine embodying the present invention;

5 Fig. 2 is a plan, partly in section on line 2—2, Fig. 1, of what is shown in Fig. 1, with the needle-cylinder, sinkers and their accessories and latch-ring removed;

10 Fig. 3 is a fragmentary sectional view on approximately line 3—3, Fig. 2;

15 Fig. 4 is an inside elevation of that part of the cam-cylinder *g* which contains the arches *x'* *y'* of the jack races or grooves;

20 Figs. 5 and 6 are sectional views on the lines 5—5 and 6—6 of Fig. 4, Fig. 6 showing only a certain inset block and its triangular piece;

Fig. 7 shows said triangular piece in plan;

25 Fig. 8 shows the means for actuating the special cams, which are arranged at the mentioned arches in the jack races or grooves;

Fig. 9 shows the jacks;

30 Fig. 10 is a fragmentary sectional view on approximately the line 10—10, Fig. 2;

35 Figs. 11 and 12 are a plan and an inside elevation of the rectifying cam means;

40 Figs. 13 and 14 are side elevations thereof and, respectively, of long-butt and short-butt needles;

45 Figs. 15, 15^a and 15^b are developments of the interior of the cam-cylinder and other parts and show the needle courses when, respectively, one series of alternate needles, then the other series, and then both clear their latches;

50 Fig. 16 shows, diagrammatically, two portions of the pattern developed, one being what I term the "fancy" portion in which the lace or tuck stitches are included and the other the "plain" portion consisting wholly of conventional knitting stitches; and

55 Fig. 17 is a diagram of a stocking produced by the improved machine.

45 The following parts of a machine to which I may apply my invention as herein set forth are all well known in the art (for instance, the mentioned Scott patent), to wit: The bed-plate *a*; the needle-cylinder *b* having latch needles *c* sliding in vertical grooves therein and also having the bevel-gear *d* journaled in a recess *d'* in the bed-plate; the bevel-gear *e* journaled in the machine frame *f* and adapted to be rotated either continuously in one direction or reciprocally by suitable means, not shown; the stationary cam-cylinder *g* having a ledge *g'* on which the needle butts may travel and recessed at the back to form the inclines *g*² and *g*³; the cams *h* *h'* in said recess each of which forms a stitch-cam or a latch-clearing cam, depending on the direction of rotation of the needle cylinder; the top and bottom center cams *i* and *i'* arranged between and cooperative with the cams *h* *h'* in their stitching and

latch-clearing functions; the web-holders or sinkers *j* arranged in radial grooves in the bed or dial *k* secured to the needle cylinder *b* and adapted to be moved radially inward and outward by the sinker cam-ring *l* which is oscillatory in a horizontal plane between adjustable limits determined by the contact of set-screws *l'* thereon with the intervening upright *m* on a part of cam-cylinder *g*; the latch-ring *n* pivoted at *o*; the switch-cam *p* for use in putting out of acting a part of the needle-group (as the long-butt needles) as when the cylinder *b* is reciprocated; the picker mechanism cooperative with said switch-cam in the operations of widening and narrowing the partial web then being formed and of which it is necessary only to indicate the narrowing pickers *q* and the widening picker *r*; and the yarn-controlling mechanism including the yarn-guides *s* (each adapted to feed yarn to the needles as the latter reach a point between cams *h* and *h'*) and the means to lower them to and raise them from working position indicated at *t*.

50 The complete needle group is divided in two respects into two distinct series; that is to say, on the one hand the alternates form one series and the remaining needles the other, and on the other hand the needles on one side of the diameter of the needle group form one series and those on the other side the other. For the separation of the needles in the first respect (alternates from the remainder) jacks *u* and *v* of different lengths are used, the long ones *u* being alternated with the short ones *v* and said jacks respectively having their butts arranged to travel in the races or grooves *x* and *y* disposed one below the other in the cam-cylinder *g*; these grooves adhere to horizontal planes throughout the whole circuit of the cam-cylinder *g* (and sufficiently low so that the jacks will not interfere with the movements, for forming the stitches, of the needles downward from the neutral plane represented by the ledge *g'* of said cam-cylinder), excepting at *x'* and *y'* where they are upwardly arched (to bring the jacks to the proper level to approximately reach and, if "called", to raise the corresponding needles, as will appear). For the separation of the needles in the second respect those within one sector (a half) of the needle group have long butts *c'* and those within the remaining sector short butts *c''*. It will be perceived from what has already been said that the separation in the first respect has to do with the production of the part of the fabric having the lace- or tuck-stitches (as at X, Fig. 17) and that the separation in the second respect has to do with the production of such circuitous portions of the fabric as in part present the lace pattern and in part the plain pattern. I shall now describe the mecha-

nisms by which the separation or division of the needles in these two respects, taking them in their order already given, is made effective in knitting:

- 5 Incidentally, it may be said that to form the lower arch x' in the race x a triangular block z is set into the inside of the cam-cylinder, the block being truncated at the top. The cam-cylinder, including this block, 10 has a vertical recess 2 formed in its outer face from top to bottom and nearly as deep as the material at this point is thick and in this is set a rectangular block 3 held in place by screws 4, the same leaving a space 15 between itself and the back of the recess for the reception of two triangular special cams 5 5' each having a stem 5^x projecting outwardly through a slot 4^x in the block and normally held depressed by a spring 6 interposed between such stem and the top of the slot. Each arch $x' y'$ at its crest has the lower side of the race at this point horizontal to form a short-cut $x^2 y^2$; when either cam 5 5' (see 5', Fig. 4) is depressed 20 the jacks travelling in the corresponding race will follow the short-cut and fail to elevate the needles, but when it is elevated (see 5) the jacks will be shunted to the extreme crest of the arch and elevate the needles. Underlying each stem 5^x is the 25 inner arm 8 of one of two levers 9 fulcrumed one above the other in a bracket 10 secured on the bed-plate a and cam-cylinder g , said levers having outer arms 11 of 30 different lengths. Underlying each arm 11 is a vertically movable pin 12 guided in a hole in the bed-plate, each pin in turn resting on one of two levers 13 pivoted under the bed-plate to move up and down and resting 35 on the periphery of a cam-wheel 14. This cam-wheel has two peripheral cam-ways each formed with two elevations 14' and two depressions 14'', the depressions in one cam-way being in central coincidence with the elevations in the other and being sufficiently 40 shorter than the elevations so that when the wheel is rotating the levers are operated as follows: First one lever will fall into a depression while the other remains elevated, 45 then both will ride on elevated portions of the two cam-ways and then the other will fall into a depression while the first lever remains elevated, then both will remain elevated, and so on, the periods (eight in all) 50 of alternating depression of one or the other lever and of elevation of both levers at once being equal, assuming the cam-wheel 14 to rotate at constant speed. The cam-wheel has peripheral teeth 15 in mesh with the 55 pinion 16 fixed to rotate with gear e , the gear-ratio being 8 to 1 so that on successive rotations of the needle-cylinder there will occur an elevation of both cams 5 5', then a depression of one cam while the other remains elevated, then an elevation of both 60 65

cams, then a depression of the other cam while the first cam remains elevated and so on.

In consequence of the foregoing it will be seen that when the needles, having undergone their stitch-forming movements (down from and back to the neutral plane g') under cam h' , successively come to pass the cams 5 5', their coincidence with the plane g' up to this point involving their being below their upper extremes of movement or latch-clearing positions, one series of alternate needles or the other or both, according as one cam 5 5' or the other or both are "called" from the cam-wheel 14, will be raised to the latch-clearing position through the medium of the jacks of one set or the other or both; in other words, in each cycle there will be either a latch-clearing movement of one of the series of needles or the other or both as they successively pass the cams 5 5'. Fig. 15 shows the cam 5' in working position and the other cam 5 depressed, so that one series of alternate needles will undergo latch-clearing and the other will not; Fig. 15^a shows the reverse arrangement of said cams and consequently that the latter series of needles will undergo latch-clearing and the former will not; and Fig. 15^b shows both cams in working position and consequently that both series of needles will undergo latch-clearing. Such needles as thus assume the latch-clearing position will next encounter cam i and then cam h' and form regular stitches (they having taken yarn just before reaching h' , as in fact all the needles always do) whereas those (if any) which do not assume latch-clearing position will enter between cams i and i' and, having taken yarn, will then be depressed by cam h' , at this point undergoing a stitch-forming or down and back movement which is abortive because they have not undergone latch-clearing. In other words, referring to Fig. 16, those needles which undergo latch-clearing will subsequently at h' form conventional stitches A, while those which do not undergo latch-clearing, although they have taken yarn, do not form conventional stitches, the yarn they take simply remaining extended across them so as to be adapted to be hung up as mere bights B, when these needles in the next course do form stitches A. On reference to Fig. 16 it will be seen that on account of the described order of the movements imparted to the special cams, since all the needles undergo latch-clearing movements on every other cycle and on the remaining cycles the two series of needles alternate as to the latch-clearing operation, there will be courses I of plain stitches alternating with courses II of alternated plain stitches and bights and that as to these two courses (II) the plain stitches in one 120

course will coincide with the bights in the other course, which in the actual fabric makes it appear diagonally striated.

- The cam h is put out of action whenever 5 the machine is producing a lace portion X (Fig. 17) of the pattern, whether such portion affects all or only a part of the circuit of the fabric. The cams 5 $5'$ and their actuating mechanism on the other hand continue 10 in operation uninterruptedly during the operation of the machine whether the fabric is being knitted with the lace pattern X or with the plain pattern Y ; and if the fabric requires at some portion a round and 15 round plain pattern, the cam h , then placed in operative position, will act to effect latch-clearing movements of all the needles, whatever distribution thereof has been effected by the cams 5 $5'$.
- 20 The cam h for the above purpose in the present instance is withdrawable independently of the other cams h' i i' ; it is shown withdrawn in Fig. 2. It is arranged on an arcuate plate 17 which has a front-to-rear 25 slot 18 (Fig. 2) at its forward end receiving a screw 19 in the horizontal or basal portion of cam-cylinder g and which also has (Fig. 1) a block 20 secured to its under side and sliding in a slot 21 formed in said basal portion, 18-19 and 20-21 forming means 30 to guide the plate rectilinearly forward and back. Following substantially the construction shown in the Scott Patent No. 1,150,547 the block may have a rearward fork 22 35 (Fig. 2) crossed by a pin 23 (Fig. 1) and receiving a slide bar 24 which has a cam 24' to engage the pin and thus withdraw the plate 17, which is normally pressed forward to bring cam h into operative position 40 by a spiral spring 25; the slide bar may be actuated from the usual pattern wheel 26* employed in knitting machines of the kind to which my invention is herein shown to be applied, so as to be called into action 45 whenever the requirements of the pattern demand.

Now as to the separation of the needles in the aforementioned second respect (i. e., so 50 that as to a half or other section of the entire needle-group the same will all have their latches cleared while as to the remaining sector the arrangement of the needles thereof as to clearing will remain as determined by the cams 5 $5'$, thus to knit circular 55 courses which go to form the fabric for a part of its circuit plain and for the remainder fancy), herein one-half of the needle-group has long butts c' and the other half short butts c'' . (The latches of all the needles are of the same length.) At a point 60 between the cams 5 $5'$ and the cam-group h h' i i' there are placed a switch or switch-cam 26 and a deflector or deflecting cam 27. The former is knife-like in form and is set 65 with its edge projecting oppositely to the

ordinary direction of movement of the needle-group for continuous or round and round knitting and so that its acting face 26' is inclined from said edge upwardly. The latter may also have a knife-like form 70 and is set with its edge projecting in the same direction as the needle-group ordinarily moves in round and round knitting and with its acting surface 27' inclined from said edge upwardly. The deflector has its 75 said edge preferably somewhat below that of the switch, and it extends toward the needle-group short of the switch a distance equal to the difference in length of the butts c' and c'' . The two are carried by a slide 80 28 arranged in a fixed bracket 29 to move radially toward or from the needle-group. The slide is normally forced outwardly by a spring 30, and it is adapted to be moved by a lever 31 against which the cam surface 85 32' of a slide-bar 32 wipes when said slide-bar is called from the pattern-wheel 26. (Lever 31 is fulcrumed in a bracket 33 which may have an arm 33' overhanging the outer end of the lever and preventing its 90 tendency to rise during the upward or working thrusts of the slide-bar.) The ledge g' has a depression 34 opposite the switch and deflector.

The cam h of course stands withdrawn 95 when the above-described cam means comprising the switch and deflector is operative on the needles, or in its inward position, since as stated it is never in the operative position when any portion of the circuit 100 of the fabric is to be knitted fancy. The cams 5 $5'$ proceed (as always) to distribute all the needles on each cycle according to the requirement then imposed by the pattern wheel 14, i. e., so that one or the other series 105 of alternate needles, or both, will undergo latch clearing. But as to the short-butt needles, whatever operation therein is effected at 5 $5'$, they all are made to undergo latch-clearing movement before they reach 110 the yarn-feeding point, to wit, as they pass the switch 26, which shifts them all upward to latch-clearing position; thus when they take yarn they will all form plain stitches course after course so as to produce the 115 plain portion Y of the fabric. The sector-series of long-butt needles each time they sweep around are shunted by the deflector 27 out of position to be acted upon by the switch, being returned to the neutral plane 120 of ledge g' as soon as they pass the switch by the inclined far side 34' of the depression 34; thus, as to the long-butt needles, whatever distribution is effected at 5 $5'$ is prevented by the deflector from being 125 prevented by the deflector from being disturbed by the switch,—every long-butt needle undergoing the shunting (those that have cleared as well as those that have not) in order to protect those that have not cleared 130

from being caused by the switch to do so. The result on the whole will be on each course to knit plain for a part thereof and fancy for the remainder, developing the portions Y and X side by side.

When the long-butt needles are shunted downwardly as last explained it will be apparent that as to those that have cleared their latches the yarn loops thereon would 10 act, as the needles descend in being shunted, to close their latches so that they would fail to take yarn at the yarn-feeding point. The latch-ring n may for this purpose have a portion n' thereof reaching downward and 15 forming a detent to prevent upward or closing movement of the latches of these needles at this time (Figs. 13 and 15, Fig. 13 showing three needles, one of which has fully descended so that the loop thereon 20 tends to close its latch, the loop itself being omitted).

Assume, for example, that it is a stocking that is to be produced, Fig. 17. Where the courses are to be knitted round and round 25 plain, as at the top, the cam h is in working position and whatever distribution of the needles is effected by the cams 5 5' this cam causes them all to clear their latches and therefore all to form stitches when they 30 take yarn and descend; the cam means 26—27 is at this time withdrawn. Where the courses are to be knitted round and round fancy, as in the leg, the cam h is withdrawn, so that it ceases to nullify the work done by 35 the cams 5 5', cam means 26—27 being also in withdrawn position. Where the courses are to be knitted in part plain and in part fancy, as around the ankle, cam h is withdrawn and cam means 26—27 is in working 40 position. Where as in forming the heel and toe the courses are back and forth, the needle-group being oscillated and only plain pattern being then wanted, the cam h is in working position (cam means 26—27 being then 45 of course withdrawn) and the machine operates the same as that of the first-mentioned Scott patent, the latch-clearing action of the cam h rectifying the effect of the cam means 5 5' on the counter-clockwise strokes the 50 same as in round and round plain knitting.

It is not indispensable that in intervals between the times when one or the other of the devices 5 5' assumes actuating position both should assume that position; but since 55 otherwise there would occur no intervening courses of plain stitches between lace forming courses, and since such courses of plain stitches result in the striations being sharply defined in the fabric, I prefer to shift 60 both devices to actuating position between each two cycles when they individually assume that position.

It is not indispensable that the two series 65 of knitting instruments, each composed of alternates, should not leave one or more in-

struments intervening between an instrument of one series and that of the other.

In Figs. 15, 15^a and 15^b one of the two series of needles (they are shown here only by their butts), regarded as separated or 70 divided in the mentioned first respect, is distinguished from the other by having their butts cross-hatched.

Having thus fully described my invention, what I claim as new and desire to secure 75 by Letters Patent is:

1. In combination, a cam cylinder having laterally open parallel grooves each formed with an arch, the apex part of that portion of the cylinder which is contained within each arch being removed, latch-clearing cams substantially conforming in shape to the parts thus removed and respectively movable up into and down out of the places from which said parts are removed, two 85 series of knitting instruments having latches and also having butts respectively engaged in said grooves and being arranged in a circular group and alternating with each other, said cylinder having cam means to 90 cause downward stitch-forming movements of said instruments and said cylinder and group of instruments being revoluble one relatively to the other around the axis of the cylinder, and means to move one of the 95 latch-clearing cams up and the other down and then vice versa during rotation as between the cylinder and group of instruments.

2. In combination, a cam cylinder having 100 a needle race and below the same laterally open parallel grooves each formed with an arch, the apex part of that portion of the cylinder which is contained within each arch being removed, a series of latch-needles having butts arranged to travel along the needle race, means to engage said butts and cause complete knitting movements of the needles including a latch-clearing cam adapted to be operatively engaged by but 105 movable out of position to engage the butts, jacks arranged below and adapted to elevate the respective needles, the alternate jacks having their butts arranged in one of said grooves and the remaining jacks having 110 their butts arranged in the other groove, other latch-clearing cams substantially conforming in shape to the said removed apex parts and respectively movable up into and down out of the places from which said 115 parts are removed, said cylinder and the group of needles and jacks being revoluble one relatively to the other around the axis of the cylinder, and means to move one of the latter latch-clearing cams up and the other down and then vice versa during rotation as between the cylinder and group of instruments.

3. A knitting machine of the circular type 120 including a circular group of knitting in- 125

struments having latches, means to impart latch-clearing movements to alternates in two sectors of the group independently of the others and in one direction from a given plane and then movements thereof toward said plane and also stitch-forming movements to substantially all said instruments in the other direction from said plane and then movements thereof toward said plane, 10 said group and means being revolute one relatively to the other to cause said movements, means to feed yarn to all the knitting instruments on each revolution, a switch, positioned to act on each revolution after 15 said latch-clearing movements have been effected and before yarn is fed to the instru-

ments, to impart to said other instruments in one sector latch-clearing movements in the first direction from said plane, means upon said latch-clearing movements of said 20 other instruments being effected by the switch to effect movements of said other instruments toward said plane, means to shift the instruments in the other sector in the opposite direction from said plane so as to 25 clear the switch, and means, during such shifting, to hold against closing the latches of those instruments in said other sector which have cleared their latches.

In testimony whereof I affix my signature.

CHARLES J. SUTPHEN.
